United States Patent Office

Des. 183,385
Patented Aug. 19, 1958

183,385

FOOD MIXER OR THE LIKE

Robert O. Ernest, Oak Park, and Ross E. Cornwell, Chicago, Ill., assignors to Sunbeam Corporation, Chicago, Ill., a corporation of Illinois

Application March 31, 1958, Serial No. 50,245

Term of patent 14 years

(Cl. D44—1)

Fig. 1 is a perspective view of a food mixer showing our new design;

Fig. 2 is a front elevational view thereof;

Fig. 3 is a side elevational view;

Fig. 4 is a top plan view;

Fig. 5 is a bottom plan view; and

Fig. 6 is a rear elevational view.

The essential features of our design reside in those portions shown by full lines.

We claim:

The ornamental design for a food mixer or the like, as shown and described.
